UNITED STATES PATENT OFFICE.

JEROME E. LYNCH, OF BOSTON, MASSACHUSETTS, ASSIGNOR TO LYNCH & WOODWARD, OF BOSTON, MASSACHUSETTS, A PARTNERSHIP COMPOSED OF JEROME E. LYNCH AND JAMES W. WOODWARD.

CONTROLLER.

1,264,313.

Specification of Letters Patent. Patented Apr. 30, 1918.

Application filed August 30, 1915. Serial No. 48,090.

To all whom it may concern:

Be it known that I, JEROME E. LYNCH, a citizen of the United States, residing at Boston, in the county of Suffolk and State of Massachusetts, have invented new and useful Improvements in Controllers, of which the following is a specification.

This invention relates to improvements in controllers particularly though not exclusively adapted for controlling and operating dampers, valves and like devices.

The object of the invention is to provide a simple, sensitive and accurate controller constructed and arranged to be operated by the application of a predetermined pressure of vapor to open or close dampers, valves and the like.

The invention consists in the combination and arrangement of parts set forth in the following specification and particularly pointed out in the claims.

Referring to the drawings:

Figure 1 is a vertical section, partly in elevation, of a controller embodying my invention, the same being operatively connected with a damper as illustrative of one specific adaptation of the device.

Fig. 2 is a transverse section taken on the line 2—2 of Fig. 1.

Like numerals refer to like parts in both views of the drawings.

In the drawings, 5 is a casing which preferably consists of an outer cylindrical portion 6 and an inner cylindrical portion 7. The upper ends 8 and 9 of said outer and inner portions respectively are closed, while the lower ends 10 and 11 of said casing members respectively are each provided with an annular flange 12 to which a ring 13 is secured, preferably by bolts 14.

The portion 7 of said casing is substantially shorter and smaller in diameter than the portion 6, thus providing an annular chamber 15 between the side walls of said casing portions and also a chamber 16 between the closed ends 8 and 9 of said casing portions. The chambers 15 and 16 constitute a float chamber within which is arranged a float 17, preferably cylindrical in shape and closed at its upper end 18, while the lower end 19 of said float is open.

The casing 5 is adapted to contain liquid, the normal level of which is slightly below the upper closed end 9 of the inner portion 7 of said casing as indicated by the line "A,"

said level being maintained by an overflow pipe 20. The liquid indicated at "A" substantially fills the chamber 15, while the chamber 16 is adapted to contain steam or other vapor which are admitted thereto under pressure through a vapor inlet pipe 21 connected with the casing adjacent to the upper wall 8 of the outer portion thereof.

The inlet pipe 21 is preferably connected with a vapor supply pipe 22 which leads from any suitable source of supply. This supply pipe is also connected to the overflow pipe 20 by means of a check valve 23, which prevents the vapor supplied through the supply pipe 22 from passing directly into the casing 5 on the level of the liquid "A" contained therein, but causes said vapor to pass upwardly to the fluid inlet pipe 21. Said check valve is however arranged to be opened by the pressure of water or liquid upon the inside of said casing when said liquid reaches the level of said valve, thus permitting the same to return to the boiler or other source from whence the vapor is supplied.

The float 17 is arranged to move vertically preferably midway between the outer and inner portions 6 and 7 of said casing in which position said float is preferably guided by means of a rod 24 secured to the end 18 of said float and passing downwardly therefrom through an opening 25 in the wall 9 of the inner portion of the casing 6. The lower end of the rod 24 is still further guided and controlled in its vertical reciprocations preferably by a cross frame 26 secured within the inner portion 7. An eye 27 is preferably formed at the lower end of the rod 24 and attached to said eye is a link 28 whose other end is pivotally attached at 29 to one end of a lever 30 preferably pivotally mounted at 31 upon a bracket 32 secured to the ring 13. The outer end 33 of said lever 30 is operatively connected in any suitable manner, preferably by a chain 34 extending over suitable pulleys 35, in the present instance with a damper 36 shown somewhat diagrammatical and whereby the movements of said float vertically will cause said damper to be opened or closed, as desired, to regulate the draft of a boiler.

A counter weight 37 is mounted preferably upon the outer arm of the lever 30 and is adjustable thereon so as to vary the weight that must be lifted by the pressure of vapor upon the float 17 before said float can be operated.

to move the damper connected with said lever. The interior 38 of the float 17 above the level of the liquid "A" is adapted to contain air which is admitted thereto through 5 the opening 25 in the stationary part of said casing, said opening being slightly larger in diameter than the rod 24. Means carried partly by the movable member or float 17 and in part mounted upon the stationary 10 portion 17 of the casing are adapted to close the opening 25 when the float 17 is depressed a predetermined amount in order to prevent the liquid in said casing from being discharged through said opening after said float 15 has reached the limit of its downward movement.

The means just described consist of a valve 39 preferably adjustably secured to the float 17, while a valve seat 40 secured to 20 the stationary portion 7 is adapted to co-operate with said valve to perform the functions hereinbefore referred to. To adjust the device so that it will operate at varying pressures to close the opening 25 the weight 25 37 may be moved toward or away from the pivot 31 of the lever 30 and thereby increase or diminish the weight to be lifted thereby.

The weight 37 co-operates with the resistance of the air from the chamber 38 in said 30 float as it escapes through the opening 25 to check the movements of said float. The size of the opening 25 is also adapted to be made larger or smaller, as desired, to increase or diminish the amount of air which is permitted to escape through said opening whereby the movements of said float will be correspondingly increased or diminished.

The means for varying the size of the 40 opening and the amount of air which is permitted to pass through said opening preferably consists of a bushing 41 which is secured in the upper wall 9 of the interior portion of said casing. The bushing 41 has a flange 42 which rests upon the upper surface 45 of the wall 9, while secured to said flange is the seat 40 for the valve 39. The bushing 41 extends through said partition 9 and is held stationary therein by screw-threads 43 upon the outer surface of the portion of 50 said bushing extending through said partition. Said bushing also extends a substantial distance below the portion 9 and is engaged by an adjustable screw-threaded cap 44 having a central hole 45 constituting a guide for the rod 24 of said float. A plurality of slots 46 are arranged about the bushing 41 and adapted to be opened or closed by the movement of the cap 44 longitudinally of said bushing. The cap 44 is 55 readily adjustable from beneath the device, permitting the same to be rotated at any time to vary the checking power of said air cushion.

The operation of the device is as follows: 60 The damper 36 may be set so that the fire

controlled thereby will produce a predetermined pressure of steam. Should the load for which the damper is adjusted be suddenly decreased the pressure of steam in the boiler will naturally be increased and 70 this increase will be transmitted to the chamber 16 against the float 17 causing said float to be depressed. The depression of the float 17 operates through the rod 24 and link 28 to rock the lever 30 upon its pivot 75 31 in opposition to the force exerted by the weight 37, thereby causing the damper 36 to close so as to check the draft of the furnace.

Should the pressure within the chamber 16 be reduced by the condensation of the steam therein or for any other reason the float 17 will be moved upwardly by the weight 37 and in consequence the damper 36 will be opened so as to increase the draft.

The downward movement of the float 17 85 will be retarded by the air within said float, which is permitted to escape, but slowly, through the passages 46, which passages may be enlarged or decreased as desired by adjusting the collar 44.

Should the pressure of the vapor within the chamber 16 continue long enough to cause the float to descend a predetermined distance, this distance being governed by the position of the valve 39 and the rod 24, said 90 valve will engage the seat 42 and thus close the passages 46, preventing the escape of the liquid in the casing 5.

It will thus be obvious that any sudden increase in the pressure of vapor entering the 100 chamber 16 will be prevented from suddenly depressing the float 17, but instead the movements thereof will be checked by the action of the air within said float which must gradually escape before said float will 105 be permitted to descend. The movement of the damper 36 will, therefore, be very slow and gradual rather than sudden. The movement of the float in the opposite direction will also be gradual for like reasons.

Having thus described my invention what I claim and desire by Letters Patent to secure is:

1. A controller having, in combination, a float provided with an air chamber, a casing 115 for said float constructed and arranged to contain liquid, said liquid constituting a seal for the air within said air chamber, an air valve communicating with the air chamber in said float, a vapor inlet for said casing adapted to direct vapor into said casing against said float to expel the air from said air chamber through said air valve and means constructed and arranged to adjust said air valve to increase or diminish the 120 amount of air passing through said valve and thereby increase or diminish the resistance to the movement of said float.

2. A controller having, in combination, a float provided with an air chamber, a casing 130

for said float constructed and arranged to contain liquid, said liquid constituting a seal for the air within said air chamber, an air valve communicating with said chamber, 5 a vapor inlet for said casing adapted to direct vapor against said float to expel the air from said air chamber through said air valve, and means constructed and arranged to vary the opening of said air valve where-

by the resistance to the movements of said 10 float may be increased or diminished.

In testimony whereof I have hereunto set my hand in presence of two subscribing witnesses.

JEROME E. LYNCH.
